CLAIM

The ornamental design for an DJ controller as shown and described.

DESCRIPTION

FIG. 1 is a top, front perspective view of my DJ controller.

FIG. 2 is a top plan view thereof.

FIG. 3 is a bottom plan view thereof.

FIG. 4 is a rear elevation thereof.

FIG. 5 is a front elevation thereof.

FIG. 6 is a left side elevation thereof; and,

FIG. 7 is a right side elevation thereof.

The broken lines show portions of the DJ controller that form no part of the claimed design.

1 Claim, 7 Drawing Sheets
